CLAIM

The ornamental design for a ceiling fan motor housing, as shown and described.

DESCRIPTION

FIG. 1 is a perspective view of a ceiling fan motor housing, shown in an environment of use;

FIG. 2 is a top perspective view of the ceiling fan motor housing of FIG. 1;

FIG. 3 is a bottom perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines illustrate portions of the ceiling fan motor housing that form no part of the claimed designs. Additional broken lines shown in FIG. 1 depict environmental subject matter and form no part of the claimed design.

1 Claim, 9 Drawing Sheets
